(57) **CLAIM**

The ornamental design for a mirror, as shown and described.

DESCRIPTION

FIG. 1 is a rear, left and top perspective view of a mirror, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front, left and top perspective view of the mirror of FIG. 1 in an alternate position of use.

FIG. 10 is another front, left and top perspective view of the mirror of FIG. 1 in an alternate position of use; and,

FIG. 11 is another rear, right and bottom perspective view of the mirror of FIG. 10.

The broken lines depict portions of the mirror that form no part of the claimed design.

1 Claim, 11 Drawing Sheets
